UNITED STATES PATENT OFFICE.

JAMES R. KING, OF PETERSBURG, INDIANA, ASSIGNOR OF ONE-FOURTH TO JAMES P. GLADISH
AND ONE-FOURTH TO WILLIAM FOUST, OF PETERSBURG, INDIANA.

CONCRETE BLOCK.

No. 884,498.

Specification of Letters Patent.

Patented April 14, 1908.

Application filed January 25, 1907. Serial No. 354,026.

To all whom it may concern:

Be it known that I, JAMES R. KING, a citizen of the United States, residing at Petersburg, in the county of Pike and State of Indiana, have invented a new and useful Concrete Block, of which the following is a specification.

This invention relates to building blocks of that general class particularly designed for use in construction of culverts, sewers, drains, rail-way bridges and the like.

The object of the invention is to provide an artificial stone building block having an over-hanging locking flange provided with an under-cut surface adapted to engage a correspondingly shaped seating recess in the opposite side of an adjacent block whereby when the blocks are laid to form a culvert the same will be effectually locked against accidental displacement.

A further object is to provide an arch or culvert, the locking flanges on the blocks of which form anchoring members for the culvert.

25 A further object is to provide a self-supporting arch or culvert having a centrally disposed locking key or block the side walls of which are provided with locking flanges for engagement with the recesses in adjacent blocks.

30 A still further object of the invention is to generally improve this class of devices so as to increase their utility, durability and efficiency.

35 Further objects and advantages will appear in the following description, it being understood that various changes in form, proportions and minor details of construction may be resorted to within the scope of the appended claim.

40 In the accompanying drawings forming a part of this specification: Figure 1 is a perspective view of a portion of a culvert constructed in accordance with my invention. Fig. 2 is a perspective view of one of the bricks or blocks detached. Fig. 3 is a similar view of the central locking block or key. Fig. 4 is an end view of the block shown in Fig. 2 of the drawings.

45 50 Similar numerals of reference indicate corresponding parts in all of the figures of the drawings.

The improved bricks or blocks are principally designed for use in the construction of culverts, drains and similar arched struc-

tures and by way of illustration several of said blocks are shown assembled in the form of an arch or culvert in which 5 designates the culvert and 6 the blocks. The blocks 6 which may be formed of cement, terra-cotta and other suitable material are preferably substantially rectangular in shape, as shown and provided with tapered side walls 7 and 8 and curved upper surfaces 8'.

Formed in one of the side walls 7 of each block at a point adjacent the curved bearing surface 8' is a longitudinal seating recess 9 defining an inclined shoulder or bearing surface 10 preferably extending the entire length of the block and adapted to receive the over-hanging flange 11 on an adjacent block when said blocks are laid to form a culvert. The longitudinal locking flanges 11 are provided with under cut surfaces or edges 12 inclined to correspond to and adapted to register with the inclined seating faces 10 of the locking recesses 9 thereby when the blocks are assembled into a wall the same will be effectually locked against accidental displacement. The opposite ends 80 of the blocks are flat and unobstructed, as indicated at 13, so as to present smooth bearing surfaces for engagement with the ends of adjacent blocks whereby the blocks may be readily laid to break joint with the flat bearing surface 13 of one block bearing against the corresponding bearing surface of an adjacent block, as best shown in Fig. 1 of the drawing. Attention is here called to the fact that the locking flanges 11 of the end or 85 foundation blocks by engagement with the ground or foundation 14 form anchoring members and thus assist in retaining the culvert or arch in position.

Each course of blocks forming the culvert 95 5 is provided with a centrally disposed supporting block or key 15 having a T shaped head under cut at 16 to form oppositely disposed locking flanges 17 similar in construction to the locking flanges 11 of the side 100 blocks, said flanges being adapted to engage the seating recesses 9 of the side blocks when the latter are laid in position to form a culvert.

In constructing the culvert the blocks are 105 laid to form an arch and arranged to break joint with the locking flange 11 of one block engaging the seating recess 9 of an adjacent block and with the flanges of the central locking key or block 15 engaging the recesses 110

of adjacent side blocks thus effectually locking the several blocks together and forming a strong, rigid and durable culvert. If desired a cement foundation may be prepared 5 and the locking flanges 11 of the terminal blocks of the culvert embedded in said cement and the latter allowed to harden or solidify or a shallow trench or groove may be formed in the earth foundation and said flanges 10 positioned within the trench and the earth thoroughly packed around the same. By having the upper surfaces of the blocks curved or convex when said blocks are laid to form an arch they will present a smooth 15 unobstructed surface while by reason of the angle or inclination of the faces 10 and 12 the blocks are firmly bound together and rendered self-supporting.

While the blocks are principally designed 20 for use in constructing culverts and the like it is obvious that the same may be employed with equally good results in the erection of walls, partitions or wherever a block of this character is found desirable.

Having thus described the invention what 25 is claimed is:

A semi-cylindrical culvert comprising a plurality of concrete arch forming blocks each consisting of an elongated substantially rect- 30 angular body portion having an upper ex- posed convex face and a flat lower face, the opposite side walls of said block being con- verged on like angles and one of said side walls provided with an integral over-hanging hook extending the entire length of the 35 block above the center thereof and depend- ing from the convex face of the block a dis-

tance equal to approximately one-third the height of said block, said hook terminating flush with the opposite ends of the block and 40 having its lower longitudinal edge under cut, the opposite side wall of each block being provided with a correspondingly shaped seating recess of the same length and height of the hook and opening 45 through said convex face, and key blocks forming part of the arch and each having its side walls converged on the same angular lines as the arch forming blocks and pro- vided with oppositely disposed over-hanging 50 hooks also disposed above the center of the block and depending from the convex face thereof a distance equal to approximately 55 one-third the height of said block, with their lower longitudinal edges under cut, said arch and key blocks being laid in superposed courses and arranged to break joint with the over-hanging hook of one arch block engag- 60 ing the seating recess of the adjacent block and with the over-hanging hooks of the key blocks engaging the seating recesses of the two adjacent arch blocks, and with the side walls of all the blocks converging towards a common center, the hooks of the terminal arch blocks being embedded in the ground 65 to form anchoring members for the culvert.

In testimony that I claim the foregoing as my own, I have hereto affixed my signature in the presence of two witnesses.

JAMES R. KING.
